Albert G. Behrens
INVENTOR.

WITNESS:

Alfred T. Bratton

BY

Victor J. Evans
ATTORNEY.

UNITED STATES PATENT OFFICE.

ALBERT G. BEHRENS, OF CAMDEN, NEW JERSEY.

CRANE.

1,333,699.

Specification of Letters Patent. Patented Mar. 16, 1920.

Application filed June 24, 1919. Serial No. 306,294.

To all whom it may concern:

Be it known that I, ALBERT G. BEHRENS, a citizen of the United States, residing at Camden, in the county of Camden and State 5 of New Jersey, have invented new and useful Improvements in Cranes, of which the following is a specification.

The invention relates to cranes and derricks and more particularly to the former 10 and has for an object to provide a crane of a simple construction consisting of few parts and which can be inexpensively manufactured.

Still further the invention comprehends 15 a crane that is preferably adapted for use in an automobile truck or the like and which therefore is carried at the rear of the truck on the chassis thereof or on some other suitable part of the body of the truck, the weight 20 of the latter being adapted to counterbalance any load that may be placed upon the post of the crane to be swung from the truck to the ground or vice versa.

In the further disclosure of the invention, 25 reference is to be had to the accompanying drawings, constituting a part of this specification, in which similar characters of reference denote corresponding parts in all the views, and in which,—

30 Figure 1— is a perspective view of the crane.

Fig. 2— is a fragmentary vertical sectional view showing the angle plate for attaching the crane, and

35 Fig. 3— is a perspective view of the blank from which the body of the crane is formed.

Referring more particularly to the views, 40 the crane consists substantially of a body or frame 10, a post 11, a block 12 and a reinforcing angle plate 13. The body or frame 10 is preferably formed of a single angle iron such as shown in Fig. 3, designated by the numeral 14, the angle iron having one side 15 thereof extending upwardly, slightly 45 beyond the other side 16 with the lower end of the side 16, extending downwardly slightly beyond the lower end of the other side 15. The upper projecting end of the side 15 is provided with an opening 17 and

is adapted to be bent over at right angles on 50 to the upper edge of the side 16 and welded thereto, thus forming a top plate 18 and similarly the extended lower end of the side 16, provided with a small opening 19 is adapted to be bent at right angles against 55 the lower edge of the side 15 and welded thereto forming a lower plate 20.

The post 11 preferably has its upper end curved in the nature of the usual davit post as used on ships and the stem 21 of the post 60 passes loosely through the opening 17 and at its lower end is formed with a stud 22 passing through the small opening 19, thus supporting the post vertically and permitting of the same being swung relative to the body. 65 The lower projecting end of the stud 22 after passing through the opening 19 may also be passed through an opening 23 in a bracket 24 the ends of which are suitably secured to a cross piece 25 which may be a part 70 of the frame of the chassis of an automobile truck, an angle plate 26 being also preferably provided and secured to the cross piece 25 and to one of the sides of the body or frame 10, thus rigidly securing the latter in 75 position.

A suitable hoisting gear 27 such as a block and tackle or a differential hoisting mechanism may be attached to the upper free end of the post and thus the crane described can 80 be conveniently employed for hoisting and swinging heavy articles from the ground on to the automobile truck or vice versa.

From the foregoing description it will be seen that the crane described is of a simple 85 construction and because of the small number and simplicity of the parts, it can be cheaply manufactured for the desired purpose.

Having described my invention, I claim,— 90
1. A crane comprising a frame and a post carried by the frame, and mounted to turn thereon, said frame consisting of an angle piece having one side thereof extended upwardly beyond the other and the other side 95 thereof extended downwardly beyond the first mentioned side, said upwardly and downwardly extended portions being bent

over their respective sides to the opposite sides to form upper and lower plates providing bearings for said posts.

2. A crane comprising a frame and a post carried by the frame, and mounted to turn thereon, said frame consisting of an angle piece having one side thereof extended upwardly beyond the other and the other side thereof extended downwardly beyond the

first mentioned side, said upwardly and 10 downwardly extended portions being bent over their respective sides to the opposite sides to form upper and lower plates providing bearings for said posts, and an attaching bracket for said frame and passing beneath 15 and against the under plate.

In testimony whereof I affix my signature.

ALBERT G. BEHRENS.
